UNITED STATES PATENT OFFICE.

MELVIN N. JORDON AND ALFRED GOAD, OF STRINGTOWN, OKLAHOMA.

TOBACCO-PIPE.

1,169,489.

Specification of Letters Patent. Patented Jan. 25, 1916.

Application filed September 18, 1914. Serial No. 862,369.

To all whom it may concern:

Be it known that we, MELVIN N. JORDON and ALFRED GOAD, citizens of the United States, residing at Stringtown, in the county of Atoka and State of Oklahoma, have invented new and useful Improvements in Tobacco-Pipes, of which the following is a specification.

The invention relates to pipes for smoking tobacco, and has for an object to provide a pipe which can be readily and quickly cleaned for the purpose of removing nicotine or other sediments or deposits from the bottom of the bowl and stem of the pipe.

The invention contemplates, among other features, the provision of a pipe which has a stem preferably formed in sections, said stem connecting a mouthpiece with the body of the pipe, with one of said sections removable from the body of the pipe and mouthpiece and adapted, in its removal, to carry the other stem sections therewith so that both stem sections can be simultaneously removed from the body of the pipe and mouthpiece and then separated and cleaned to remove any sediments or deposits therefrom.

In the further disclosure of the invention reference is to be had to the accompanying drawings, constituting a part of this specification, in which similar characters of reference denote corresponding parts in all the views, and in which:

Figure 1 is a vertical longitudinal sectional view taken through the pipe, showing the pipe assembled; Fig. 2 is a similar view, showing the lower stem section partially removed and in position to carry the upper stem section therewith; Fig. 3 is a perspective view, showing the stem sections disengaged for cleaning; and Fig. 4 is a vertical transverse sectional view taken on the line 4—4 in Fig. 1.

Referring more particularly to the views, I disclose a pipe 10 consisting, more particularly, of a bowl 11 having a tubular shank 12 communicating with the bowl 11, a suitable tubular mouthpiece 13 being provided and connecting with the tubular shank 12 by a stem 14 consisting of an upper stem section 15 and a lower stem section 16, said stem sections being each semi-circular in cross section, with the lower stem section 16 longer than the upper stem section 15 and having its inner end projecting into the bottom of the bowl, whereas the inner end of the upper stem section 15 extends up to the bowl of the

pipe. The outer ends of the stem sections lie exteriorly of the mouthpiece and terminate in heads 17 and 18 respectively, which abut against the mouth end of the mouthpiece as shown. The inner extremity of the lower stem section 16 has a projection 19 which bears against a wall of the bowl and limits the movement of the lower stem section, and the mouthpiece 13 is preferably provided with a notch 20 adjacent the head 18 of the stem section 16. Now assuming that the stem becomes clogged with nicotine or some other deposit or foreign matter, when it is desired to clean the same, the finger nail is inserted in the notch 20 and a pull exerted against the head 18 of the lower stem section 16, thus causing the lower stem section to be moved in the shank 12 and be removed by way of the mouthpiece 13. As the lower stem section is moved in the shank, it will be seen that the projection 19 will bear against the front end of the upper stem section and will thus cause the upper stem section to be removed with the lower stem section, as shown in Fig. 2. The stem sections, when removed from the mouthpiece, and shank, are separated and can then be readily cleaned out to remove any foreign matter therefrom.

When the stem sections are in position in the shank 12 as shown in Fig. 1 and connect the shank 12 and mouthpiece 13 as shown in the same figure, it will be seen that the projection 19 of the lower stem section 16, bearing against a wall of the bowl, will act as a guide to guide the nicotine or any foreign matter into the projecting end of the lower stem section so that when the stem sections are subsequently removed such deposits or foreign matter can be easily cleaned out of the lower section as well as the upper section which will be removed simultaneously with the lower stem section in the manner set forth.

Having thus described our invention, we claim:

A tobacco pipe having a cleaning device consisting of upper and lower stem sections providing a tubular passage, said lower stem section projecting beyond the upper stem section and having its inner end extending into the bowl, a projection on the inner end of the lower stem section and adapted to engage the inner end of the upper stem section to work the removal of the upper stem section from the shank of the bowl of the

pipe and mouthpiece of the pipe when the lower stem section is removed from the shank and mouthpiece, the projection on the inner end of the lower section being normally spaced a distance from the inner end of the upper section for permitting nicotin and the like being collected in the extended portion of the lower stem section, and said projection when engaging with the upper 10 stem section serving to close the inner end

of the tubular passage for preventing any accidental displacement of the nicotin therefrom during the removal from the pipe.

In testimony whereof we affix our signatures in presence of two witnesses.

MELVIN N. JORDON.
ALFRED GOAD.
